nesota

Application August 24, 1933, Serial No. 686,572

3 Claims. (Cl. 122—155)

This invention relates to processes and devices for supplying heated humidified air.

It is the general object of the invention to provide a novel and improved humidifying process whereby humidified air at a relatively high temperature may be supplied to a space to be both humidified and heated.

Another object is to provide a novel and improved device of cheap and simple construction, 10 which can be effectively utilized for supplying heated and humidified air.

A further object is to provide a novel and improved steam boiler, which can be utilized with the utmost efficiency to generate steam.

15 The objects and advantages of the invention will more fully appear from the following description, made in connection with the accompanying drawings, wherein like reference characters refer to the same or similar parts throughout the various views, and, in which,

Fig. 1 is a view in front elevation of a device embodying the invention;

Fig. 2 is a view taken partly in side elevation and partly in vertical longitudinal section through the device, certain of the parts being broken away to more clearly show the construction thereof;

Fig. 3 is a view partly in side elevation and partly in vertical section of the inner shell of the boiler;

Fig. 4 is a horizontal section taken on the line 4—4 of Fig. 3, as indicated by the arrows; and

Fig. 5 is a horizontal section taken on the line 5—5 of Fig. 3, as indicated by the arrows.

35 In accordance with the invention, there is provided a casing 6 preferably of rectangular shape in cross section and having preferably at its rear near its lower end a cold air inlet 7. At the top of the casing 6 preferably spaced somewhat forwardly from the rear side of the casing there is provided a warm air outlet 8 communicating with an air conduit 9 adapted to convey heated, moistened air to the room or chamber to be heated and humidified. Mounted within 40 the casing 6 and closing the lower forward portion of the casing is a water boiler which may be designated as an entirety by the letter A. This boiler is of special construction hereinafter more fully described. From the upper central portion of the boiler A a conduit 10 for conveying off the products of combustion after they have passed through the boiler, runs to an annular drum 11 disposed within the casing 6. This drum 11 is preferably of cylindrical shape as shown 45 to provide a central vertical air passage 12 con-

centric with the outlet 8. The conduit 10 is connected to an inlet 13 at the forward side of the drum near its upper end, and this conduit serves to support the forward portion of the drum within the casing 6. The drum 11 is equipped with an outlet 14 at its rear side adjacent its upper end, preferably in diametrically opposed relation from the inlet 13. The outlet 14 runs through an opening in the rear of the casing 6 and, in practice this outlet will be connected up 10 to a smoke flue or chimney (not illustrated). The outlet 14 supports the rear part of the drum 11 from the casing 6. The inner and outer walls of the drum are spaced from each other to provide a heating chamber 15 and the products of combustion are baffled by means of baffle plates 16 within the chamber 15, so that the products of combustion will have a long travel between the inlet 13 and the outlet 14 to give up a great portion of their heat to the air surrounding the drum 15 and to the air within the air passage 12. The baffles 16 preferably are interposed about midway between the front and rear portions of the drum so as to extend between the outer and inner walls of the drum and these baffles run from 20 the top of the drum downwardly to points spaced upwardly somewhat from the bottom of the drum. With this arrangement, it will be seen that the products of combustion entering the drum through the inlet 13 will be divided to move 25 arcuately through the heating chamber 15, first downwardly below the baffles 16 and thence upwardly to the outlet 14.

Connected to the steam space at the upper end of the boiler A is a steam pipe 17 which runs 35 first upwardly and then rearwardly to connect with a steam distributing head 18 of substantially ring-shape. This head is preferably located immediately above the air passage 12 in the drum and below the outlet 8 and the head is provided with a plurality of perforations 18a through which the steam running to the head may exhaust upwardly into the air within the casing 6.

The boiler A is best illustrated in Figs. 2, 3, 4 and 5. The boiler includes a lower section 19 45 having a front opening closed by a removable plate 20 through an opening in which an oil burner (not illustrated) may be inserted within the section. The upper part of the lower section 19 is double walled to provide a lower water chamber 21, the inner wall of which forms the fire pot of the boiler. Overlying the top of the lower section 19 and extending well above the same are inner end outer shell sections or shells 22 and 23 respectively, which together define a chamber 24 50 55

for water and steam. The inner shell 22 is provided with an outturned ring-like flange 25 at its lower end, which rests on packing material 26 overlying the top of the lower section 19. The outer shell 23 is provided with an outturned flange at its lower end and this flange, the flange 25 and an outturned flange at the upper end of the lower section 19 are connected together by a number of bolts 27. A plurality of nipples 28 mounted in the flange 25 and in the upper wall of the lower section 19 afford communication between the chamber 21 and the chamber 24. The shell 23 is of general cylindrical shape and it has an inturned flange at its upper end connected to a flange 29 of the inner shell 22. The inner shell 22 is of quite peculiar shape and it may be considered to comprise a lower part 30 of generally regular polygonal shape having vertical outer walls connected together by channel-like ribs 31. These ribs 31 project much farther inwardly at their lower ends than at their upper ends and the inner edges of the ribs extend from their lower ends diagonally upwardly and outwardly to connect with a circular flange 32 at the top of the lower part of the inner shell. In the particular embodiment shown, seven ribs are provided although it will be understood that any desired number of ribs may be used if desired. The inner shell 22 may be also considered to include an upper part 33 which is also of regular polygonal shape in general exterior contour but of considerably smaller size than the lower part 30. The upper part 33 joins the inner edge of the flange 32 and the exterior walls of the upper part are vertical. The exterior walls are connected by means of a plurality of inwardly extending ribs 34 of general channel shape in cross section. These ribs 34 join the inner edge of the flange 32 and run diagonally upwardly and inwardly as best shown in Fig. 3, to connect at their upper ends with the flange 29. It should be here noted that the ribs 31 of the lower part 30 do not align with the ribs 34 of the upper part 33. In other words, the ribs 34 are staggered relative to the ribs 31. The inner surfaces of the inner shell 22 may be considered to define a space for the travel of the products of combustion which is similar to that formed by two ribbed truncated pyramids having their larger bases in abutment. The flange 29 is provided with an upstanding ring 35 which connects with the conduit 10.

It will be seen that the boiler A is provided through the medium of the inner shell 22 with an exceedingly large surface area in direct contact with the heated products of combustion. Accordingly, the water within the chamber 24 will be very quickly heated to generate steam in the upper part of the chamber. To supply water to the chamber 24 and to maintain the water in the chamber at a constant level, there is provided a water inlet conduit 36 provided with a chamber 37 having mounted therein a float valve 38 of standard construction and not illustrated in detail.

When the device is set in operation, the prod-

ucts of combustion from the boiler after passing through the same to heat the water in the chamber 24 and generate steam therein, will run through the conduit 10 into the drum 11 to heat the air surrounding the drum and the air in the air passage 12. Cool air will be admitted to the casing 6 through the inlet 7 and will pass upwardly around the drum 11 and through the air passage 12 to a point over the drum. The steam generated in the chamber 24 will pass through the steam conduit 17 into the steam head 18 from whence it will be discharged through the apertures 18a. This steam will mix with the heated air above the drum 11 to cause this air to be thoroughly moistened. Due to the fact that the air is heated before the steam is mixed with the same, the air more readily absorbs the moisture from the steam to prevent the formation of fog. The heated and moistened air will then pass through the outlet 8 to be conveyed by the conduit 9 to the room or chamber to be heated and humidified.

It will be seen that the one unit will supply both heated and humidified air. Practically all the heat is utilized to heat the air within the casing 6 and the device is accordingly most efficient in operation. The device has been successfully demonstrated in actual practice.

It will, of course, be understood that various changes may be made in the form, details, arrangement and proportions of the various parts without departing from the scope of the present invention, which generally stated, consists in the matter shown and described and set forth in the appended claims.

What is claimed is:—

1. A steam boiler comprising a combustion chamber and inner and outer shells defining a boiler chamber, said outer shell being of substantially cylindrical shape and having an upper wall joining the upper edge of the inner shell, said inner shell being ribbed from bottom to top to define an inner open space produced by applying two truncated ribbed pyramids with their larger bases in abutment.

2. A water boiler comprising a combustion chamber and an outer and an inner shell above said combustion chamber, said outer shell being substantially cylindrical in shape and having an upper end joining the upper edge of the inner shell, said inner shell having a lower substantially cylindrical portion and an upper substantially cylindrical portion of smaller size than the lower portion, said lower portion having a plurality of inwardly projecting ribs formed therein, said ribs projecting diagonally upwardly and outwardly from their lower ends, said upper portion also having a plurality of ribs formed therein, said ribs projecting upwardly and inwardly from their lower ends.

3. The structure defined in claim 2, the ribs of said upper portion being circumferentially staggered relative to the ribs of said lower portion.
